(57) **CLAIM**

The ornamental design for a water tile, as shown and described.

DESCRIPTION

FIG. 1 is a front perspective view of a water tile according to the present invention;

FIG. 2 is a left side elevational view of the water tile of FIG. 1, the right-side, top-side, and bottom side elevational views each being a mirror image thereof; and,

FIG. 3 is a front elevational view of the water tile of FIG. 1. The rear of the water tile is unornamented;

1 Claim, 3 Drawing Sheets

FIG. 1

FIG. 2

FIG. 3
